UNITED STATES PATENT OFFICE.

ARTHUR W. SMITH, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,110,407.

Specification of Letters Patent. Patented Sept. 15, 1914.

Original application filed March 8, 1913, Serial No. 752,848. Divided and this application filed June 20, 1913. Serial No. 774,761.

To all whom it may concern:

Be it known that I, ARTHUR W. SMITH, a citizen of the United States, and resident of the borough of Manhattan, city of New York, in the county of New York, and State of New York, have invented certain new and useful Improvements in Type-Writing Machines, of which the following is a specification.

10 My invention relates to typewriting and like machines, and the object of the invention is to provide simple and efficient automatically operating means for arresting the carriage at different points at successive 15 return movements of the carriage, in order to facilitate writing addresses, for example, on work sheets or cards.

To the above and other ends which will hereinafter appear, my invention consists in 20 the features of construction, arrangement of parts and combinations of devices set forth in the following description and particularly pointed out in the appended claims.

In the accompanying drawings in which 25 like reference characters designate like parts in the various views, Figure 1 is a fragmentary plan view of one form of typewriting machine embodying my invention. Fig. 2 is a detail fragmentary front elevation of the means for arresting the carriage in its return movement and some of the associated parts. Fig. 3 is a detail perspective view of a portion of the carriage arresting means. Figs. 4, 5 and 6 are detail front 35 elevations of the same with parts in section and parts broken away, these views illustrating the parts disposed as they appear in different conditions of use.

The present case is a division of my application Sr. No. 752,848, filed March 8th, 40 1913.

While I have shown my invention embodied, in the present instance, in a typewriting machine having needle faced types, 45 and one intended primarily for "writing" or preparing stencil cards or sheets, it should be understood that the invention is applicable to typewriting and like machines generally, and that the novel devices of the 50 invention may be regarded in the nature of an attachment which may be readily affixed to various styles of typewriting machines without modifying, or materially

modifying, the structural features of those machines as they now exist.

55

In the present embodiment of the invention the frame of the machine is of the usual construction, such as that employed in the Nos. 10 or 11 Remington machines and in which a top plate 1 supports fixed front and rear guide rails 2 and 3 respectively. The carriage comprises front and rear guide rails or cross-bars 4 and 5 respectively and end bars 6. Anti-friction balls or rollers are received between the guide rails 2 and 4, and 65 3 and 5 and support the carriage for movement over the top plate of the machine.

In the present instance the carriage supports a hopper or chute 7 which receives a series of work sheets or cards 8 which are 70 automatically fed to work sheet feeding means, not shown. Such work sheet feeding means are controlled by a handle 9 that is effective to return the carriage to the right to begin a new line of writing and to simultaneously actuate a link 10 by which the work sheet feeding means are controlled and by which the cards or work sheets are successively fed to a platen 11 carried by the carriage.

75

The carriage is propelled from right to left, or in the direction of its feed, by a spring drum 12 to which one end of a band 13 is connected, the other end of the band being connected to a bracket 14 secured to 80 the carriage by screws 15.

The carriage has a step by step letter space movement from right to left under control of the usual escapement mechanism (not shown) and is limited in such movement by a stop 16 secured to the top plate by a screw 17. In the return movement of the carriage to the right it is arrested by the novel devices of my invention at different points which are successively nearer the 95 middle of the machine, as will hereinafter appear.

Type bars 18 are segmentally arranged and mounted in the frame of the machine to move upwardly and rearwardly and to impact against the front face of the platen. As shown in the present instance, each type bar has a needle faced type 19, the types being employed for preparing stencil sheets or cards. The type bars are actuated by any 100 suitable key controlled actuating means,

105

110

115

such as those employed in the Remington machines mentioned above.

The automatically operating means for variably arresting the carriage in its return movement to begin a new line of writing, and by which the carriage is arrested at different positions which are progressively near the center of the machine at different return movements of the carriage, may be said to consist in the main of two members, one carried by the carriage and the other by the frame of the machine. Thus, the right hand supporting plate 20, which is connected to and travels with the carriage and may be regarded as a part thereof, has a bracket 21 secured thereto by screws 22. This bracket has an arm 23, which extends to the right and constitutes a support for a screw pivot 24. From an inspection of Figs. 1 and 2, it will be understood that the screw 24 passes freely through an opening in one side member or ear 25 of a sheet metal pawl or stop member, designated as a whole by the reference numeral 26. The opposite or parallel wall 27 of this pawl is tapped to receive the threaded end of the screw 24. This screw also passes freely through an opening in the projection 23 and receives a bearing therein by which the pawl is pivotally supported in place. The upper wall of the pawl which joins the two side members 25 and 27 is adapted to bear upon the upper surface of the projection 23 (see Fig. 2) to limit the downward movement of the pawl. This pawl or stop member terminates at the right hand end in an engaging nose 28.

A bracket plate 29 is secured by screws 30 to the top plate 1 of the machine at the right-hand side thereof. The bracket plate is formed with an upwardly extending plate-like projection 31 provided with a series of teeth or stops 32, 33, 34. These stops are in the nature of ratchet teeth which are inclined upwardly from right to left and form in effect a ratchet bar or rack.

The pawl 26 traveling with the carriage normally has a path of movement which is indicated by the dotted line showing of said pawl in Fig. 4. The upper edge of the plate 31, at the inner end thereof, is beveled at 35 in order to lift the pawl against its own weight when the end of the pawl is brought into co-operation with the bevel. Ordinarily an arrest of the carriage would be effected by the pawl entering the space to the left of the tooth 32, which is the first tooth the pawl would encounter in its movement to the right with the carriage. However, I have provided controlling means for controlling the engagement of the pawl with the different stops or teeth 32, 33, 34. The controlling means in the present instance comprises a controlling member, device or shield 36 which is in the nature of a slide and has a rectilinear movement, being supported by

headed screws 37 which extend through a slot 38 in the part 36 and are received at their threaded ends in tapped openings in the plate 31. This sliding plate is provided with three teeth or engaging portions 39, 40 and 41. Intermediate these engaging portions the upper edge of the controlling member is provided with dwells 42, 43, 44. A contractile spring 45 is connected at one end to a pin or hook 46 which projects from the plate 31, the opposite end of the spring being connected to a pin 47 which projects from one side of the controlling member 36. The force of this spring is exerted to pull the controlling member to the left. A pawl 48 is pivoted by a headed screw 49 to the controlling member 36 and the engaging nose 50 of this pawl is adapted to co-act with ratchet teeth 51 formed on a block 52 which is fixed to the plate 31 by screws 53. The ratchet teeth 51 terminate in a cam 54 formed on the upper edge of the block and with which the engaging nose of the pawl is adapted to co-act. This pawl is forced into engagement with its ratchet teeth by a wire spring 55 fixed at one end to the controlling member by a screw 56. The opposite end of the spring is received in an opening 57 (see Fig. 4) formed in the hub of the pawl 48.

A leaf spring 58 is fixed to the bracket plate 29 by rivets 59. The left-hand end of the spring is bent forwardly and then upwardly and then rearwardly to form a flat upper portion 60 which overlies the engaging nose 50 of the pawl 48 and forms a controlling device which co-operates therewith. Normally the portion 60 of the spring 58 is free from engagement with the nose 50 of the pawl but as the controlling member is moved to the right relatively to the stop carrying member 31, the engaging portion of the pawl would be brought into contact with the lower face of the part 60 of the spring, as shown in Fig. 5, thus elevating the free end of the spring. A movement of the controlling member from the position shown in Fig. 5 to that indicated in Fig. 6 is effective to cause the pawl 48 to lift the spring, and after the engaging portion of the pawl is withdrawn from beneath it to allow the part 60 to resume its normal position. At this time the engaging portion of the pawl in its return movement is adapted to contact with the upper side of the part 60 of the spring, thereby maintaining the pawl out of engagement with the ratchet teeth 51 during the return movement of the controlling member 36, as indicated by dotted lines in Fig. 6.

It being understood that Fig. 3 shows the normal position of the parts, and that these parts are disposed as shown when the carriage is moved to the right to begin the first line of writing, it will be seen that in this movement of the carriage the pawl 26 will

engage the dwells 42 and 43 on the controlling member, the pawl being thereby prevented from entering the notches of the first two teeth 32 and 33. But when the pawl 5 reaches the opening in front of the tooth 34 it will enter this opening, engaging the face 41 on the controlling member and moving said member to the right with the stop or pawl 26 until the latter is arrested by engaging the fixed stop 34. This movement of the controlling member is effective to carry the pawl 48 with it from the position shown in Fig. 3 to that represented in Fig. 4, which latter figure shows the disposition of the 10 parts at the termination of the movement of the carriage to the right to begin the first line of writing. The pawl 48 engaging the first tooth 51 will retain the controlling device 36 in the position to which it has been 15 shifted. The operator proceeds to write the first or name line and when this is completed the operator will again move the carriage to the right through an actuator of the handle 9, and at this time the controlling device 36 being in the position shown in Fig. 4, the dwell 42 will prevent the pawl 26 from engaging the notch in advance of the first tooth 32, but will enable the pawl to enter the notch in advance of the tooth 33. As the 20 pawl enters this second notch it will engage the contact portion 40 on the controlling device, thus moving the controlling device from the position shown in Fig. 4 to that represented in Fig. 5, which last mentioned 25 figure shows the disposition of the parts at the termination of the second return movement of the carriage to begin the second line of writing. 30

A comparison of Figs. 4 and 5 will show 35 that the carriage is arrested in its second return movement at an earlier period than in the return movement of the carriage for the first line of writing, thus properly arresting the carriage so as to offset the beginning of the second line, or the first line of the address. The parts are substantially in the position 40 represented in Fig. 5 when the carriage is returned the second time. This will leave the controlling member 36 in the position shown in Fig. 5 where the dwell 42 no longer prevents the pawl 26 from entering the notch in advance of the tooth 32 on the next return movement of the carriage. After the 45 second line has been completed the carriage will be returned to the right and the pawl 26 will enter the notch in advance of the first tooth 32 and will engage the face or contact portion 39 on the controlling member, forcing the latter to the right and carrying with 50 it the pawl 48. The pawl 48 at this time moves up the incline 54 and releases itself from engagement with the spring member 60, as shown in Fig. 6. This view represents the parts as they appear at the termination 55 of the return movement of the carriage to

begin the third line of writing. As hereinbefore explained, when the controlling portion 60 is lifted by the engaging nose 50 of the pawl 48 in the movement of the latter to the position shown in full lines in Fig. 70 6, the part 60 as soon as released from control of the pawl 48 will be returned to normal position by its spring 58, so that the pawl 48 is prevented during the return movement of the controlling device 36 from 75 engaging with the ratchet teeth 51. As the carriage moves to the left in writing the third line the controlling device 36, under the power of its spring 45, will move to the left until the right-hand end of the slot 38 80 in the controlling member engages the right-hand screw 37. At about the termination of the return movement of the slide 36 the pawl will pass the left-hand end of the contact member 60 and will be forced to the lower- 85 most position shown in Fig. 3. It will be seen, therefore, that during the writing of the third line the controlling device 36 and the pawl 48 will return to the normal position which they occupied prior to returning 90 the carriage for beginning the first line of writing. It will be understood that the arrest of the carriage in its movement to the right, through the coöperation of the pawl 26 with the stop or tooth 32, effects an arrest 95 of the carriage at an earlier point in its return movement than is effected by the co-operation of the pawl with the stop 33, so that a further offsetting of the beginning of the third line of writing is effected. 100

It will be seen from the foregoing description that the controlling member 36 is intermittently actuated by the movement of the carriage to the right to control the engagement of the pawl with the stops or 105 teeth 32, 33, 34, and that the carriage is arrested at points progressively nearer the left-hand side of the machine while arresting the carriage preparatory to writing the three lines to be inscribed on the stencil 110 plate. While I have shown three stops 32, 33 and 34, it should be understood that any suitable number of such stops may be employed, appropriate modification of the controlling member 36 being made accordingly. 115

In the parent application, of which the present case is a division, there are various features in the mechanism for effecting a feed of the cards, which have elements in common with the construction forming the 120 subject-matter of the present divisional application, and there are claims included in the parent case which have been drawn to cover this common subject-matter or construction generically. Thus, each mechanism includes a toothed device, a coöperating pawl and automatically operating controlling means for determining with which tooth of the toothed device said pawl or co-acting member shall coöperate. Each 125 130

mechanism also includes means for restraining the controlling means in different positions to which it may be shifted, or a detent for holding the controlling member 5 against the power of its spring, and also automatically operating means for reestablishing the normal relation between the controlling member and the toothed member after a given number of actuations of said 10 controlling member. In each case the controlling member is in the nature of a toothed device which is actuated by the same pawl that coacts with the other toothed member. In each case the controlling member is in 15 the nature of a shield which prevents the coöperating pawl from engaging certain teeth of a toothed member, and in each case the shield is automatically actuated to determine with which tooth of the toothed member the pawl shall engage. In each case the pawl coöperates with a toothed member which is in the nature of a rack.

The claims in the present divisional case are restricted to that form of the construction which is shown herein, and the parent case contains generic claims which cover or include this construction.

What I claim as new and desire to secure by Letters Patent, is:—

30 1. In a typewriting machine, the combination of a carriage; and automatically operating means for arresting the carriage at different points at successive movements of the carriage, said means comprising a 35 plurality of stops fixed on the part of the machine which supports such stops, a co-acting stop, and automatically operating means for controlling said coöperative stop to enable it to engage the plurality of stops 40 successively at successive movements of the carriage.

2. In a typewriting machine, the combination of a carriage; and automatically operating means for arresting the carriage 45 at different points at successive movements of the carriage, said means comprising a plurality of stops fixed on the part which supports such stops, a co-acting stop, and automatically operating means co-acting 50 with said coöperative stop for controlling and enabling it to engage the plurality of stops successively at successive movements of the carriage, said controlling means being operated by said co-acting stop.

55 3. In a typewriting machine, the combination of a carriage; and automatically operating means for arresting the carriage at different points at successive movements of the carriage, said means comprising a 60 plurality of stops, a co-acting stop, and automatically operating means coöperating with and controlling said co-acting stop to prevent it from co-acting with different of the plurality of stops at successive movements of the carriage to thus determine with

which of the plurality of stops the co-acting stop may coöperate at each movement of the carriage.

4. In a typewriting machine, the combination of a carriage; and automatically operating means for arresting the carriage at different points at successive movements of the carriage, said means comprising a plurality of stops, a co-acting stop, a shield coöperative with said co-acting stop to prevent it from coöperating with certain of the plurality of stops, and means by which said shield may be automatically shifted to determine with which of the plurality of stops the co-acting stop may co-act. 75

5. In a typewriting machine, the combination of a carriage; and automatically operating means for arresting the carriage at different points at successive movements of the carriage, said means comprising a 80 plurality of stops, a co-acting stop, a shield coöperative with said co-acting stop to prevent it from coöperating with certain of the plurality of stops, and means by which said co-acting stop is rendered effective to shift 85 said shield and thereby determine with which of the plurality of stops the co-acting stops may co-act and thus vary the position of arrest at successive movements of the carriage. 90

6. In a typewriting machine, the combination of a carriage; and automatically operating means for arresting the carriage at different points at successive movements of the carriage, said means comprising a 100 plurality of stops, a co-acting stop, a shield coöperative with said co-acting stop to prevent it from coöperating with certain of the plurality of stops, and means by which said shield is intermittently shifted at successive movements of the carriage to determine with which of the plurality of stops the co-acting stop may coöperate at each movement of the carriage and thus automatically 105 vary the positions of arrest of the latter. 110

7. In a typewriting machine, the combination of a carriage; and automatically operating means for arresting the carriage at different points at successive movements of the carriage, said means comprising a plurality of stops, a co-acting stop, a shield coöperative with said co-acting stop to prevent it from coöperating with certain of the plurality of stops, means by which said shield is intermittently shifted at successive movements of the carriage to determine with which of the plurality of stops the co-acting stop may coöperate at each movement of the carriage and thus automatically vary the positions of arrest of the latter, and automatically operating means for returning said shield to normal position after a predetermined number of shifting movements. 115

8. In a typewriting machine, the combi- 120

130

nation of a carriage; and automatically operating means for arresting the carriage at different points at successive movements of the carriage, said means comprising a plurality of stops, a co-acting stop, automatically operating controlling means coöperating with said co-acting stop to prevent it from co-acting with different of the plurality of stops at successive movements of the carriage to thus determine with which of the plurality of stops the co-acting stop may coöperate at each movement of the carriage, and means for restraining said controlling means in different of the positions to which it may be moved.

9. In a typewriting machine, the combination of a carriage; and automatically operating means for arresting the carriage at different points at successive movements of the carriage, said means comprising a plurality of stops, a co-acting stop, automatically operating controlling means coöperating with said co-acting stop to prevent it from co-acting with different of the plurality of stops at successive movements of the carriage to thus determine with which of the plurality of stops the co-acting stop may coöperate at each movement of the carriage, means for restraining said controlling means in different of the positions to which it may be moved, and automatically operating releasing means for releasing said restraining means and allowing the controlling means to return to normal position.

35 10. In a typewriting machine, the combination of a carriage; and automatically operating means for arresting the carriage at different points at successive movements of the carriage, said means comprising a plurality of stops, a co-acting stop, a shield co-operative with said co-acting stop to prevent it from coöperating with certain of the plurality of stops, means by which said shield may be automatically shifted to determine with which of the plurality of stops the co-acting stop may co-act, and automatically operating means for restraining said shield in different positions to which it may be shifted.

50 11. In a typewriting machine, the combination of a carriage; and automatically operating means for arresting the carriage at different points at successive movements of the carriage, said means comprising a plurality of stops, a co-acting stop, a shield co-operative with said co-acting stop to prevent it from coöperating with certain of the plurality of stops, means by which said shield may be automatically shifted to determine with which of the plurality of stops the co-acting stop may co-act, automatically operating means for restraining said shield in different positions to which it may be shifted, and automatically operating

straining means and allowing it to return to normal position.

12. In a typewriting machine, the combination of a carriage; and automatically operating means for arresting the carriage at different points at successive movements of the carriage, said means comprising a plurality of stops, a co-acting stop, automatically operating controlling means coöperating with said co-acting stop to prevent it from co-acting with different of the plurality of stops at successive movements of the carriage to thus determine with which of the plurality of stops the co-acting stop may coöperate at each movement of the carriage, and a pawl and ratchet for holding said controlling means in different positions to which it may be moved.

20 13. In a typewriting machine, the combination of a carriage; and automatically operating means for arresting the carriage at different points at successive movements of the carriage, said means comprising a plurality of stops, a co-acting stop, automatically operating controlling means coöperating with said co-acting stop to prevent it from co-acting with different of the plurality of stops at successive movements of the carriage to thus determine with which of the plurality of stops the co-acting stop may coöperate at each movement of the carriage, a pawl and ratchet for holding said controlling means in different positions to which it may be moved, and automatically operating means for separating said pawl and ratchet and allowing a return movement of said controlling means to normal position.

25 14. In a typewriting machine, the combination of a carriage; and automatically operating means for arresting the carriage at different points at successive movements of the carriage, said means comprising a plurality of stops, a co-acting stop, a shield co-operative with said co-acting stop to prevent it from coöperating with certain of the plurality of stops, means by which said shield may be automatically shifted to determine with which of the plurality of stops the co-acting stop may co-act, and a pawl and ratchet for holding said shield in different positions to which it may be shifted.

30 15. In a typewriting machine, the combination of a carriage; and automatically operating means for arresting the carriage at different points at successive movements of the carriage, said means comprising a plurality of stops, a co-acting stop, a shield co-operative with said co-acting stop to prevent it from coöperating with certain of the plurality of stops, means by which said shield may be automatically shifted to determine with which of the plurality of stops the co-acting stop may co-act, a pawl and ratchet for holding said shield in different

- positions to which it may be shifted, and automatically operating means for separating said pawl and ratchet and enabling said shield to return to normal position.
- 5 16. In a typewriting machine, the combination of a carriage; and automatically operating means for arresting the carriage at different points at successive movements of the carriage, said means comprising a 10 pawl and a rack, the different teeth of the rack which are engaged by said pawl determining the position of arrest of the carriage.
- 15 17. In a typewriting machine, the combination of a carriage; and automatically operating means for arresting the carriage at different points at successive movements of the carriage, said means comprising a pawl and a rack, the different teeth of 20 the rack which are engaged by said pawl determining the position of arrest of the carriage, and automatically operating controlling means for bringing about engagement between said pawl and successive teeth 25 of the rack at successive movements of the carriage.
- 30 18. In a typewriting machine, the combination of a carriage; and automatically operating means for arresting the carriage at different points at successive movements of the carriage, said means comprising a pawl and a rack, the different teeth of 35 the rack which are engaged by said pawl determining the position of arrest of the carriage, a controlling device for controlling the engagement between said pawl and the different teeth of said rack, and automatically operating means for shifting said controlling device.
- 40 19. In a typewriting machine, the combination of a carriage; and automatically operating means for arresting the carriage at different points at successive movements of the carriage, said means comprising a 45 pawl and a rack, the different teeth of the rack which are engaged by said pawl determining the position of arrest of the carriage, a controlling device for controlling the engagement between said pawl and the 50 different teeth of said rack, automatically operating means for shifting said controlling device, and automatically operating means for restraining said controlling device in different positions to which it may 55 be shifted.
- 60 20. In a typewriting machine, the combination of a carriage; and automatically operating means for arresting the carriage at different points at successive movements of the carriage, said means comprising a pawl and a rack, the different teeth of 65 the rack which are engaged by said pawl determining the position of arrest of the carriage, a controlling device for controlling the engagement between said pawl and the 70 different teeth of said rack, automatically operating means for shifting said controlling device, and a pawl and ratchet for holding said controlling device in different positions to which it may be shifted.
- 75 21. In a typewriting machine, the combination of a carriage; and automatically operating means for arresting the carriage at different points at successive movements of the carriage, said means comprising a pawl and a rack, the different teeth of 80 the rack which are engaged by said pawl determining the position of arrest of the carriage, a controlling device for controlling the engagement between said pawl and the different teeth of said rack, automatically 85 operating means for shifting said controlling device, and a pawl and ratchet for holding said controlling device in different positions to which it may be shifted.
- 90 22. In a typewriting machine, the combination of a carriage; and automatically operating means for arresting the carriage at different points at successive movements of the carriage, said means comprising a pawl and a rack, the different teeth of 95 the rack which are engaged by said pawl determining the position of arrest of the carriage, a controlling device for controlling the engagement between said pawl and the different teeth of said rack, automatically 100 operating means for shifting said controlling device, a pawl and ratchet for holding said controlling device in different positions to which it may be shifted, and automatically operating means for separating 105 said pawl and ratchet and allowing said controlling device to return to normal position.
- 110 23. In a typewriting machine, the combination of a carriage; and automatically 110 operating means for arresting the carriage at different points at successive movements of the carriage, said means comprising a pawl and a rack, the different teeth of the rack which are engaged by said pawl determining the position of arrest of the carriage, a shield with which said pawl co-acts and which prevents the pawl from entering a space between certain teeth of the rack depending on the position of said shield, and 115 means for moving said shield.
- 120 24. In a typewriting machine, the combination of a carriage; and automatically operating means for arresting the carriage at different points at successive movements 125 of the carriage, said means comprising a pawl and a rack, the different teeth of the rack which are engaged by said pawl determining the position of arrest of the carriage, a shield with which said pawl co-acts and 130

which prevents the pawl from entering a space between certain teeth of the rack depending on the position of said shield, and automatically operating means for shifting said shield at each return movement of the carriage.

25. In a typewriting machine, the combination of a carriage; and automatically operating means for arresting the carriage at different points at successive movements of the carriage, said means comprising a pawl and a rack, the different teeth of the rack which are engaged by said pawl determining the position of arrest of the carriage, a shield with which said pawl co-acts and which prevents the pawl from entering a space between certain teeth of the rack depending on the position of said shield, automatically operating means for shifting said shield at each return movement of the carriage, means for restraining said shield in different positions to which it may be shifted, and automatically operating means for releasing said restraining means and for allowing said shield to return to normal position.

26. In a typewriting machine, the combination of a carriage; and automatically

operating means for arresting the carriage at different points at successive movements of the carriage, said means comprising a pawl and a rack, the different teeth of the rack which are engaged by said pawl determining the position of arrest of the carriage, a shield with which said pawl co-acts and which prevents the pawl from entering a space between certain teeth of the rack depending on the position of said shield, automatically operating means for shifting said shield at each return movement of the carriage, a pawl and ratchet for holding the shield in different positions to which it may be shifted, means for separating said last mentioned pawl and its ratchet, means for preventing a reengagement between the pawl and its ratchet until the shield has returned to normal position, and a spring for returning the shield to normal position.

Signed at the borough of Manhattan, city of New York, in the county of New York and State of New York, this 19th day of June, A. D. 1913.

ARTHUR W. SMITH.
